US0D1041852S

(12) **United States Design Patent** (10) Patent No.: **US D1,041,852 S**
(45) Date of Patent: ** Sep. 17, 2024

(54) SHOE	D205,026 S	6/1966	Rosenbaum et al.
(71) Applicant: NIKE, Inc. , Beaverton, OR (US)	3,965,516 A	6/1976	Romero et al.
(72) Inventors: Thomas Belhacene , Portland, OR (US); Earl Stewart , Portland, OR (US); Philip Woodman , Treviso (IT)	D243,642 S	3/1977	Voorhees

CLAIM

The ornamental design for a shoe, as shown and described.

DESCRIPTION

FIG. 1 is a bottom view of a shoe showing our new design; FIG. 2 is a side view thereof; and,

FIG. 3 is an opposite side view thereof.

The broken lines depicting the remainder of the shoe form no part of the claimed design.

1 Claim, 3 Drawing Sheets

FIG. 1

FIG. 2

FIG. 3
